Specification for Design.

Patented Aug. 27, 1918.

Application filed April 16, 1917. Serial No. 162,574. Term of patent 14 years.

To all whom it may concern:

Be it known that I, JOHN C. BOYTON, a citizen of the United States, residing at Cleveland, in the county of Cuyahoga and State of Ohio, have invented a new, original, and ornamental Design for Conduit-Fittings, of which the following is a specification, reference being had to the accompanying drawing, forming part hereof, wherein—

Figure 1 is a perspective view, Fig. 2 a side elevation, Fig. 3 a left hand end elevation, Fig. 4 a right hand end elevation, and Fig. 5 a bottom plan view of the conduit fitting exhibiting my new design.

I claim:—

The ornamental design for a conduit fitting as shown.

JOHN C. BOYTON.
